United States Patent Office.

GEORGE W. PUTNAM, OF BOSTON, MASSACHUSETTS.

Letters Patent No. 82,750, dated October 6, 1868; antedated September 26, 1868.

IMPROVEMENT IN LANTERNS.

The Schedule referred to in these Letters Patent and making part of the same.

TO ALL WHOM IT MAY CONCERN:

Be it known that I, GEORGE W. PUTNAM, of Boston, in the county of Suffolk, and State of Massachusetts, have invented a new and useful Improvement in Lanterns; and I do hereby declare that the following is a full, clear, and exact description thereof, which will enable others skilled in the art to make and use the same, reference being had to the accompanying drawings, forming part of this specification.

This invention relates to a new and useful improvement in that class of lanterns which are designed to be more portable than the ordinary or original kind, and which are adjustable, so as to be capable, when not in use, of being closed, or arranged so that one part may be fitted within the other.

The invention consists in using, in connection with a lantern of this class, a movable magazine, for holding candles, matches, and other articles necessary to be used with a lantern.

In the accompanying sheet of drawings—

Figure 1 is a vertical section of my invention, taken in the line $x' x'$, fig. 2.

Figure 2, a vertical section of the same, taken in the line $x'' x''$, fig. 1.

Figure 3, a side view of the same adjusted for use.

Figure 4, an inverted plan or bottom view of the same.

Similar letters of reference indicate corresponding parts.

A represents the case of the lantern, which is provided, at one side, with a handle, B, so applied that it may be turned close against the side, and be entirely out of the way, when not required for use.

This case may be of any suitable or desired form, but I prefer to have it with at least one end or side curved in semicircular form.

C represents a case, constructed so as to correspond in form to the case A, but somewhat smaller, so that C may slide within A, as shown in figs. 1 and 2.

This case C has a metal strip, a, attached to each side of it, and these strips work through loops, b, attached to the inner surfaces of the opposite sides of the case A, the strips and loops serving as guides for the case C, and also as stops.

The case C is cut out at its curved or semicircular end, and at the greater portion of its two adjoining parallel sides, and in this space a piece of mica or other transparent material, c, is placed.

D is what I term a magazine, constructed of sheet metal, and of such dimensions that it may, when the lantern is not in use, be fitted within the case C, the case A being provided with a cover, d, which, when removed, admits of the magazine being fitted in C.

The magazine is also provided with a cover, e, and it is designed to contain candles, matches, the candle-stick or socket, and any other article which is to be used with the lantern.

One end of the magazine has a hook-projection, f, attached to it, and the corresponding end of the case C is provided with a loop, g.

When the lantern is adjusted for use, the case C drawn down from A, and the magazine D removed from case C, the hook-projection f is fitted in the loop g of case C, as shown in fig. 3, and the magazine is thus carried when the lantern is in use.

This I consider the most preferable plan, although, if desired, the magazine, which is not very large, may be carried in the pocket.

By this invention, the lantern may be made much more portable or smaller than it otherwise could be, as the magazine for holding the articles necessary to be used with the lantern is made separate from it, and, when the lantern is not in use, may be placed within it, and, when the lantern is in use, may be suspended to one side of it, entirely out of the way, so as not to interfere with the carrying of the lantern in the least.

When the magazine is inserted in the case C, the hook-projection f is inserted in a loop, g', at the inner side of the case, (see fig. 1.)

I claim as new, and desire to secure by Letters Patent—

The employment or use, with a portable lantern, of a movable magazine, when all are constructed and arranged substantially as shown and described.

GEORGE W. PUTNAM.
